UNITED STATES PATENT OFFICE.

ARTHUR FRANCIS SECREST, OF WICHITA, KANSAS.

GARMENT.

1,383,491.

Specification of Letters Patent.

Patented July 5, 1921.

Application filed July 31, 1919. Serial No. 314,415.

To all whom it may concern:

Be it known that I, ARTHUR FRANCIS SECREST, a citizen of the United States, and a resident of Wichita, in the county of Sedgwick and State of Kansas, have invented 5 certain new and useful Improvements in Garments, of which the following is a specification.

My invention relates in general to garments and more particularly to outer protective garments either of the ordinary overall type or of the combination jacket and trouser or union garment type.

An important object of my invention is to 10 provide a garment which will freely, easily and automatically adjust itself to all movements and positions of the body of the wearer and which will relieve of any strain or pull the shoulders or other parts not well 15 adapted to bear the same and evenly distribute any such pull or strain over parts best adapted to bear the same.

Another object is to provide a garment of 20 this type which is neat and comfortable and 25 easy and inexpensive to manufacture.

Other objects and advantages reside in 30 certain novel features of the construction, arrangement and combination of parts which will become apparent as the description 35 proceeds, reference being had to the accompanying drawings forming part of this specification and in which—

Figure 1 is a perspective view of a combination jacket and trouser garment embodying my invention and showing the garment in use,

Fig. 2 is a front elevational view of the garment, the front being unbuttoned and thrown back and parts thereof being broken 40 away, for the sake of illustration,

Fig. 3 is an elevational view showing the rear of the garment, parts being broken away for the sake of illustration,

Fig. 4 is a perspective view showing my 45 invention embodied in a garment of the overall type the garment being shown in use,

Fig. 5 is a perspective view, the parts thrown open for the sake of illustration,

Fig. 6 is a detail view showing the form, 50 arrangement and points of suspension of the seat flap extensions,

Fig. 7 is a rear view of the overall type 55 of garment showing the garment in use and the wearer in erect position,

Fig. 8 is a side view of the overall type showing the wearer in bending position.

Referring to Figs. 1, 2 and 3 of the drawings, it will be seen that the embodiment of the invention shown in these figures comprises a body portion in the form of a jacket 60 10 open at the front and adapted to button along the median or central line thereof and having integral with said front, trousers 11. A reinforcing strip 10' may be provided 65 along the waist line if desired. The trousers are provided with a seat flap 12 having extensions 13 integral therewith. These extensions are preferably triangular in form and are so arranged that they extend outwardly and upwardly away from the central or median line of the seat flap as particularly shown in Figs. 2 and 6. The extreme upper ends of the extensions are provided with buttons 14, the purpose of which is to 70 be hereinafter more fully described. The marginal edges of the seat flap proper are provided with suitable buttons 15 which co-operate with button-holes 15' provided in the adjacent marginal edges of the trousers. 75

Above the waist line and near each of the side edges of the jacket front, as shown in the drawing, are secured button-hole tabs 16, by means of suitable stitching or the like. These tabs are secured to the under side of 80 the jacket and are provided with suitable button-holes 16'. The buttons of the seat flap extensions are adapted to be engaged in these button-holes when the garment is 85 in position on the wearer.

When the garment is in position on the wearer as previously described, the seat flap and its extensions are concealed by the cover flap 17 which is preferably integral with the back of the jacket and hangs downwardly 90 therefrom.

Referring to Figs. 4, 5 and 6 of the drawing, it will be seen that the embodiment of my invention shown in these figures comprises overalls provided with the trouser 100 section 18, a body portion in the form of a bib 19 and if desired a reinforcing strip 20 around the waist line of said overalls. A seat flap 21 is preferably formed integral 105 with the trouser section and is also provided with seat flap extensions 22 which are also triangular in form and extend outwardly and upwardly away from the central or median line of said seat flap. These seat flap extensions are provided at their outer 110

extremities with button-holes 23 which co-operate with buttons 24 secured to tabs 25 fastened by stitching or the like to the inner side of the bib 19. It is to be understood 5 however that if desired the tabs 25 may be provided with button-holes and the extensions with buttons as in the previous instance.

A neck strap 26 has one end fixed to one 10 upper corner of the bib and the other end is adapted to be secured to the other upper corner of said bib by a buckle 27 or a button and button-hole or the like.

The construction, arrangement of parts 15 etc., is practically the same for both embodiments of the invention but as all of the features of operation are identically the same a single description of the operation applies equally well to both forms of 20 the invention.

It is apparent that the point of suspension of the seat flap extensions is the point of suspension of a major portion of the garment especially during certain movements 25 and in certain positions of the body of the wearer. This point of suspension is so disposed vertically above the waist line and horizontally around to the front of the garment and the seat flap extensions 30 are of such form and so arranged with respect to this point of suspension that in certain movements of the body, such as a bending movement the strain and pull which have hitherto been applied to the 35 shoulders and other parts not adapted to bear the same are translated into strains extending transversely around the body along lines upwardly inclined toward the front at a slight angle or inclination to the horizontal. This has the effect of tightening 40 the bib or jacket against the body of the wearer and thereby preventing the undesirable sag of these portions. On returning 45 to erect posture the garment automatically returns to its natural position being supported by its conformation to the body contour and by the shoulders in the case of the union garment and the neck strap in the case of the overall.

50 It is to be understood however that all pull or strain due to any movement or position are not imposed upon the shoulder

or neck strap but are taken up along substantially horizontal lines around the body as previously described. It is obvious that 55 in this manner any necessity for shoulder straps or suspenders is entirely eliminated.

The triangular shaped extensions may be made adjustable if desired.

I claim:

1. A garment consisting of a jacket, trousers integral with the front thereof, a seat flap integral with the back of the trousers having triangularly shaped extensions extending outwardly and upwardly 65 away from the center of said seat flap and being provided with buttons at the extreme upper ends thereof, tabs provided with button-holes attached to the under side of the front of said jacket and adapted to receive 70 the buttons of said seat flap extensions and a cover flap adapted to conceal said seat flap and extensions when the garment is in position on the wearer.

2. A garment consisting of a jacket, 75 trousers integral with the front thereof, a seat flap integral with the back of the trousers having triangularly shaped extensions extending outwardly and upwardly 80 away from the center of said seat flap and being provided with buttons or other suitable fasteners at the extreme upper ends thereof, and tabs provided with button-holes attached to the under side of the front of said jacket and adapted to receive the buttons of said seat flap extensions. 85

3. A garment consisting of a body portion, trousers associated therewith, a seat flap on said trousers having triangularly formed extensions extending outwardly and 90 upwardly from the center of said seat flap to the side edges thereof adapted to be attached to the under side of the front of said body portion.

4. A garment consisting of a body portion, 95 trousers associated therewith and a seat flap on said trousers having two triangularly formed extensions extending outwardly and upwardly from the center of said flap and adapted to be attached to the 100 body portion, substantially as and for the purposes set forth.

ARTHUR FRANCIS SECREST.
